(No Model.)

L. J. ODELL.

CHECK ROW PLANTER.

No. 289,696.

Patented Dec. 4, 1883.

UNITED STATES PATENT OFFICE.

LEVI J. ODELL, OF FAIRBURY, ILLINOIS, ASSIGNOR OF TWO-FIFTHS TO HENRY KINGMAN, WESLEY WALTON, AND ISAAC WALTON, ALL OF SAME PLACE.

CHECK-ROW PLANTER.

SPECIFICATION forming part of Letters Patent No. 289,696, dated December 4, 1883.

Application filed July 5, 1883. (No model.)

To all whom it may concern:

Be it known that I, LEVI J. ODELL, a citizen of the United States, residing at Fairbury, in the county of Livingston and State of Illinois, have invented a new and useful Check-Row Planter, of which the following is a specification, reference being had to the accompanying drawings.

This invention relates to check-row planters; and its object is to provide a device of this class possessing superior advantages in point of simplicity, inexpensiveness, durability, and general efficiency.

In the drawings, Figure 1 is a rear perspective view of the front portion of a corn-planter, showing my check-row mechanism in position. Fig. 2 is a detail perspective view of the gear-wheel mechanism. Fig. 3 is a sectional view taken through the rotary shaft that carries the crank-disk. Fig. 4 is a detail sectional view of the crank disk and pawl. Fig. 5 is a detail perspective view of the connection of the tappet-wire fork with the rock-shaft.

Referring to the drawings, A designates the frame of the corn-planter, on which are mounted the seed boxes or hoppers B B, through which works the transverse reciprocating slide C in the usual manner.

D is a cross-bar that is secured on top the seed-boxes, and is provided with cross-pieces E E, arranged one at each end, and having bearings F F for the transverse main rock-shaft G, to the ends of which are secured the

forks H H, that are operated by the tappet-wire to actuate the said rock-shaft.

The foregoing mechanism may be of any ordinary or suitable construction.

The rock-shaft G has a bearing in a plate, I, projecting forwardly from the cross-bar D, and a gear-wheel, J, (or a segment of a wheel, as herein shown,) is keyed or otherwise secured on the rock-shaft near this bearing.

K is a rotary shaft that is longitudinally disposed in relation to the planter, and has its bearings through the cross-bar D. This shaft K carries at its rear end a crank-disk, L, while a gear-wheel, M, (or a segment of a wheel, as herein shown,) is loosely arranged on its front projecting end, N, this wheel M

being in engagement with the wheel J, and having a front ratchet-face, O, as shown. When the rock-shaft G is caused to turn by action of the tappet-wire, the gear-wheel J will cause the wheel M to turn, and the ratchet-face O of the latter will engage with a spring-actuated ratchet-disk pawl, P, fixed on the square end of the shaft K, so that this said shaft will be carried around by the loose wheel M. When the tappet disengages from the fork H, the shaft G is brought back to its normal position by action of a spring, Q, on the fork, and the wheel J engages the wheel M in the opposite direction; but during this movement the wheel M will be merely turned on the shaft K and the pawl will slide over the face O, while the said shaft K will remain stationary until by the operation of the next tappet upon the forks it will be turned again by the wheel M engaging the pawl. By means of this mechanism the rock-shaft has only a rock motion back and forth, while the shaft K has a rotary intermittent motion. This rotary intermittent motion of shaft K of course turns the crank-disk L, the pin R of which enters a longitudinally-disposed slot, S, in the top end of a rock-lever, T, that is pivoted on a bracket, U, projecting from the cross-bar D, and is provided at its lower end with a slot, V, that is connected with a slotted standard, W, on the seed-slide C by a pin, X. By the movement of this rock-lever T, caused by the intermittent rotary movement of the disk L, the seed-slide is reciprocated.

The operation and advantages of my invention will be readily understood and appreciated. It is exceedingly simple and inexpensive in construction, and operates with superior efficiency.

The rock arms or forks H H are preferably arranged to loosely turn on the rock-shaft G, which latter is provided with end pins, Y, that engage a shoulder, Z, on the forks, so that the rock-shaft will be turned by action of the forks. In this way the forks on the rock-shaft will operate independently and alternately, as one will remain stationary while the other is in engagement with the pin to turn the rock-shaft.

The crank-disk L is preferably provided with a ratchet-face, A², that is engaged by a gravity-

pawl, B², to retain the rotary shaft from backward movement while the rock-shaft is returning.

I am aware that check-rower mechanism has been heretofore constructed with a rotary shaft adapted to transmit its motion to reciprocate the seed-slide and operated by the rock-shaft, the movement of the rotary shaft being intermittent and caused by the movement of the rock-shaft in one direction. I therefore do not broadly claim this.

I claim as my invention—

As an improvement in check-row corn-planters, the combination, with the transverse bar D, of the rotary shaft K, journaled through the same, and provided at its rear end with the crank-disk L, having the ratchet portion A², and at its front end with the disk P, locked

against rotary movement on the shaft, and having the inner ratchet-face, the gear M, loosely arranged on the shaft between the disk P and bar D, and having the outer ratchet-face, the spring acting on disk P' to force it into engagement with gear M, the pawl B², engaging portion A² to hold shaft K from reverse movement, and mechanism acting upon gear M to turn it alternately in opposite directions, substantially as set forth.

In testimony that I claim the foregoing as my own I have hereto affixed my signature in presence of two witnesses.

LEVI J. ODELL.
